UNITED STATES PATENT OFFICE.

EDWARD C. LORENTZEN, OF KENDRICK TOWNSHIP, GREENE COUNTY, IOWA.

BOTTLE-VENDING MACHINE.

1,224,942.

Specification of Letters Patent.

Patented May 8, 1917.

Application filed March 16, 1915. Serial No. 14,834.

To all whom it may concern:

Be it known that I, EDWARD C. LORENTZEN, a citizen of the United States, residing in Kendrick township, in the county of Greene and State of Iowa, have invented a new and useful Bottle-Vending Machine, of which the following is a specification.

My invention relates to coin controlled machines for dispensing small packages.

10 It is my object to provide such a machine having a suitable magazine adapted to properly feed bottles or the like in such a manner as to avoid breaking the bottles.

15 A further object is to provide such a device, whereby the bottles next to the discharge aperture are passed through a refrigerator chamber, or cooling means, so that they may be served cold.

20 Still a further object is to provide in such a device a suitable receiving magazine for the empty bottles.

25 A further object is to provide in such a mechanism, a feeding machine of new and novel construction adapted to be controlled by coins or slugs.

Still a further object is to provide in such a machine suitable means for returning a coin when the empty bottle is returned to the machine.

30 My invention further consists in the construction, combination and arrangement of the various parts of the device, whereby the objects contemplated are attained, as hereinafter more fully set forth, pointed out in my claims and illustrated in the accompanying drawings, in which:

Figure 1 shows a front elevation of the cabinet in which the mechanism of my improved bottle vending machine rests.

40 Fig. 2 shows a vertical sectional view of the same taken on the line 2—2 of Fig. 1.

Fig. 3 shows a detail sectional view taken on the line 3—3 of Fig. 2.

Fig. 4 shows a detail sectional view taken 45 on the line 4—4 of Fig. 3.

Fig. 5 shows a detail sectional view taken on the line 5—5 of Fig. 3.

Fig. 6 shows a detail view of a pawl and toothed member of the sliding coin receiving bar.

Fig. 7 shows a vertical sectional view through the mechanism for returning a coin when an empty bottle is returned to the machine.

50 Fig. 8 shows a transverse vertical sec-

tional view of the same taken on the line 8—8 of Fig. 7, and

Fig. 9 shows a vertical sectional view on the line 9—9 of Fig. 8.

In the accompanying drawings, I have used the reference numeral 10, to indicate generally a cabinet which contains the mechanism of my improved bottle vending machine. The cabinet is provided with doors 11 and 12, which may be opened for supplying bottles to the feeding magazine and removing the bottles from the receiving magazine, and removing the coins from the coin receptacle.

Suitably mounted within the cabinet between the upper and lower end thereof, is a pan or receptacle 13, designed to receive ice 13^a and to hold water 13^b, for cooling the bottles, as hereinafter described.

A suitable discharge pipe 28 is mounted 75 in the bottom of the receptacle 13 and extends to a point above the bottom thereof for maintaining the water in said receptacle at the desired level. Below the tube 28 is a waste water receptacle 29 supported on a 80 bracket 30. The receptacle may be removed through the door 12.

A transverse shaft 14 is suitably mounted in bearings within the cabinet 10, and on the shaft 14 is mounted a drum 15, having a 85 plurality of longitudinal pockets 16 in its outer surface, designed to receive the bottles 17, as herein later explained.

Starting near the upper rear portion of the interior of the cabinet, is a channel 18 90 which has openings at its rear end, and is inclined slightly downwardly and forwardly to the front of the cabinet. A second channel 19 communicates with the front lower end of the channel 18 communicates 95 with a similar channel 20, which extends forward and slightly downward in the cabinet to a position below the upper level of the drum 15, and in the rear of the longitudinal center thereof. Bottles 17 are fed 100 in the channel 18 from the rear end thereof, until all the channels, above described, are full. Parts are so arranged that only one bottle can pass from one channel to the other at a time. The pockets 16 in the drum 15 are so arranged that each pocket will receive one bottle and no other bottle will be discharged from the channel 20 until another pocket approaches the lower end of said channel.

A shield 21 extends around the lower portion of the drum 15 from the lower edge of the channel 20 to a point on the forward side of the drum 15 slightly below the horizontal middle thereof. Extending downwardly and outwardly from the forward end of the shield 21, is a delivery way, or channel 22 at the outer end of which is a pocket 23 for holding the bottle 17, until removed by the customer.

In the front wall of the cabinet 10 just below the receptacle 13 is an opening 24 which communicates with a series of channels 25, 26, and 27, which communicates successively with each other, and are in each case inclined slightly downwardly and across the cabinet, being in general of similar construction to the channels 18, 19, and 20. The channels 25, 26, and 27 constitute a magazine for the reception of empty bottles, while the channels 18, 19, and 20, constitute a supply magazine.

Outside the drum 15 at one end thereof a pinion 31 is mounted on the shaft 14 in mesh with a pinion 32, loosely mounted on a counter shaft 33.

The pinion 32 is provided at regular intervals with teeth 34, which are longer than the remainder of the teeth of said pinion.

In the exemplification of my invention illustrated in the accompanying drawings, I have shown a pinion 32 with every third tooth longer than the other teeth on the pinion. Fixed to the pinion 32 is a ratchet

35. Mounted on the shaft 23 adjacent to the ratchet 35 is an operating lever 36 which extends forward in the machine through a vertically elongated slot 37 in the front wall of the cabinet. Pivoted to the lever 36 is a

40 pawl 38, adapted to coact with the ratchet 35 for rotating the ratchet 35, and the gear 32 in one direction. Mounted on the casing wall above the level of the pinion gear 32 is a bracket or supporting member 39 having a

45 lateral extension 40, to which is secured a coil spring 41. The coil spring 41 is also secured to the lever 36, and serves to yieldingly hold the lever at the upper limit of its movement. The slot 37 serves to limit the

50 movement of the lever 36 in both directions.

Fixed to the front wall of the cabinet on the interior thereof, adjacent to the slot 37, is a toothed bar 42, which is curved on the arc of a circle having its center in the longitudinal axis of the shaft 33. Pivoted between its ends to the lever 36 adjacent to the bar 42 is a pawl 43. Secured to the rear end of the pawl 43 and to the pin 44 mounted on the lever 36 is a coil spring 45, adapted to hold the pawl 43 parallel with the lever 36. When the lever 36 is pushed downwardly, the tooth of the bar 42 engages the pawl 43 and tilts its forward free end slightly upwardly until the free end of the

55 pawl 43 clears said bar, as the lever 36 con-

tinues to move downwardly. The pawl 43 and toothed bar 42 are so arranged that the said pawl prevents the upper movement of said lever 36 until the pawl 43 clears the lower end of the bar 42, after which the lever 36 may be moved upwardly, and the pawl 43 will slide over the teeth of the bar 42.

Slidably mounted in the bracket extension 40 and in suitable guides 46 is a vertical rod 47. Pivoted to the bracket at its rear end is a forwardly extending member 48, having at its forward end a downwardly inclining hook member 49, the lower edge of which is beveled at 50. The sliding rod 47 is pivoted to the member 48 near the forward end thereof. The horizontal portion 40 of the bracket 39, extends forwardly in the machine through an opening 51 therein, and is formed with a shoulder 52, spaced inwardly from the front wall of the cabinet. The sides of the portion 40, at the forward end thereof, are bent upwardly to form guides 53 for the coin carrying plate 54, which slides freely on the member 40, and between the guides 53. At its outer end, the coin carrying plate 54 has an upward extension 55 to serve as a handle. The plate 54 is secured at its rearward end at 56 to a member 57, the upper surface of which is inclined upwardly and forwardly from its rear end at 58. At the upper end of the inclined portion 58 is a notch or slot 59. The member 57 slides in an opening in the upright member 47. A coil spring 60 is secured to a lug 61 on the plate 54 and to the front wall of the casing, and tends to hold the plate 54 at the forward limit of its movement.

In the extension 40 within the cabinet and between the shoulder 52 and the forward wall of the cabinet, is an opening 62, designed to permit a coin to pass through the member 40. In the plate 54 is a coin receiving opening 55, designed to be outside the cabinet when the plate 54 is at the forward limit of its movement, and to register with the opening 62 when the plate 54 is at the rear limit of its movement. The plate 54 is of substantially the same thickness as the coin, to be used to operate the machine.

Slidably mounted just inside the front wall of the cabinet above the plate 54 is a vertical bolt 63, having on its lower end a head 64 which travels in a guideway 65. If the plate 54 is pushed rearwardly into the cabinet without a coin in the plate or slot 54, the head 64 will travel into the opening 55, and prevent the plate 54 from reaching the rearward limit of its movement. If, however, a coin is placed in the slot 55 before the plate 54 is pushed inwardly, then the head 64 will travel over the coin, and will not prevent the movement of the plate 130

54. The lower face or surface of the head 64 is beveled from its rear edge, upwardly and forwardly, so as to permit the return of the plate 54 from its rear to its forward position. A spring 66 yieldingly holds the rod 63 and the head 64 at the lower limit of their movement.

It will be seen from the foregoing description, that the rearward movement of the plate 54 and the member 57 with its beveled upper edge will cause the member 47 to be raised, thereby raising the member 48, and lifting the hook 49 until the lower end of the hook member 49 stands above the pinion 32 at such a point that it will clear the shorter teeth of the pinion. The operation of the parts will now be more fully described.

At the beginning of each operation, the pinion 32 stands in such position that the hook member 49 is just past one of the longer teeth 34, and must pass two shorter teeth before engaging another of the longer teeth. It will be assumed that the feed magazine is full, and that the pockets of the drum 15 have been filled. The coin is inserted in the opening 55 and the slide bar 54 is pushed inwardly. The member 64 will slide over the coin and permit the slide bar 54 to be pushed to the inward limit of its movement. For requiring the making of the complete inward stroke of the bar 54, the edge thereon on the inside of the casing, is provided with teeth 67. Pivoted to the extension 40 is a pawl 68, one end of which is secured to the bolt 44. At each end of the series of teeth 67 is a notch 70. Before the commencing of the inward stroke 54 the free end of the pawl 68 stands received in the notch 70, at the left hand of said series of teeth, as shown in Fig. 6. It will be seen when the stroke is commenced, the pawl 68 will engage the teeth and prevent the outward stroke of the slide bar 54, until the inward stroke of said bar has been completed, and the pawl enters the right-hand notch 70. The slide bar 54 is pushed inwardly, carrying with it the member 57, the beveled edge 58 of which engages the member 47 and pushes the same upwardly until the notch 59 is reached, when the member 47 drops into said notch. When the parts have reached this position, the hook 49 is raised until its beveled edge will clear the shorter teeth of the gear 32. The handle 36 is grasped and forced downwardly, the pawl 38 engages the ratchet 35, which is fixed to the pinion 32, and the gear 31 is thereby rotated a part of a revolution, thereby rotating the gear 31, the shaft 14, and the drum 15. As has already been explained, the pawl 43, and notched bar 42 make it impossible for the lever 36 to return to its starting position, until its downward stroke has been completed. As the pinion

32 is rotated, the hook member 49 clears two of the shorter teeth. The beveled edge 50 then engages the longer tooth, whereby the hook member 49 is raised, thereby raising the member 48 and the member 47, until the member 47 clears the notch 50, whereupon the spring 60 will return the members 57 and 54 to their original positions. The member 48 is normally held downwardly by a spring 71. When the hook member 49 passes the longer teeth, the lever 36 reaches the downward limit of its stroke, and the drum 15 reaches a proper position for delivering one of the bottles 17 to the pockets 23. The coin is dropped through an opening 62 into a coin chute 72, from whence it is delivered to a receptacle 73. The empty bottles may be put into the channel 25 and delivered to the receiving magazine.

It will be understood that the channels for receiving the bottles are so inclined that the bottles travel slowly down them which prevents the breaking of the bottles.

My device is of comparatively simple and durable construction, and is simple and easily operated.

Owing to the construction and arrangement of the parts, several bottles are always in the ice cold water, while the whole cabinet is cooled and serves as a refrigerating chamber.

Parts are so arranged that each stroke of the lever 36 moves the drum 15 a proper distance for delivering one bottle through the discharge aperture in the front of the cabinet. The bottles are easily placed in the feeding magazine, and removed from the lower magazine.

In Figs. 7 and 8 of the drawings, I have shown an exemplification of the mechanism for returning the coin when an empty bottle is returned to the machine.

It is well known that in selling soft drinks, such as pop and ginger ale and the like, it is frequently necessary to charge for the bottle, and to make a return payment when the bottle is returned.

I have provided mechanism for making the return payment in a bottle vending machine. In mesh with the gear 32 is a gear 80, on a shaft 81. The gear 80 is also in mesh with a gear 82, shown by dotted lines in Fig. 7, on a shaft 83. On the shaft 83 is a larger gear 84. Mounted on still another shaft 85 is a mutilated gear 86, shown by dotted lines in Fig. 7, and having gear teeth at a distance equal to one-fourth of its periphery, then a blank space for one-fourth, and then gear teeth for one-fourth, then a blank space for one-fourth, as shown in said figure. The teeth on the gear 86 are designed to mesh with the teeth at the gear 84, when the gear 86 is in proper position.

Mounted on the shaft 85, and fixed with relation to the gear 86, is a ratchet 87, shown

by dotted lines in Fig. 7. Pivoted to the shaft 85 is an arm 88, shown by dotted lines. Pivoted on the arm 88 is a pawl 89, adapted to coact with the ratchet 87. Pivoted to the lever or arm 88 is a link 90, suitably mounted on the casing 10. At a point between its ends is a lever 91, one end of which is pivoted to the link 90, and the other end of which, extends through a suitable slot in front of the casing to a position outside the cabinet or casing, where it is within easy access of an operator.

It may be noted that the ratchet 87 and pawl 89, and link 90, are so constructed and arranged that one stroke of the lever 91, when the ratchet is in the proper position, will move the ratchet, and consequently the gear 86 one-fourth of a revolution, or a sufficient distance to move the gear 86, from position, where one set of teeth thereon will mesh with the teeth on the gear 84, to position where the other set of teeth thereon, will mesh with the teeth on the gear 84.

Mounted on the shaft 85 is a drum 92, similar to the drum 15, hereinbefore described. An intake channel 93, extends through the front wall of the chamber 10, and is located with its inner end adjacent to the drum 92. On the opposite side of the drum 92 is a channel 95, adapted to receive bottles from the drum 92, and forming a part of a receiving magazine composed of the channels 94, 95, and 96.

Suitably mounted within the cabinet 10, is a vertical coin holding tube 99, supported above a plate 100. Slidably mounted in suitable guides on the upper surface of the plate 100 is a coin moving slide bar 101, in which is an opening designed to slide beneath the tube 99, and to receive one coin at a time, from said tube. The spring 102 normally holds the slide bar 101, at the rearward limit of its movement.

Communicating with a suitable opening in the plate 100 and extending downwardly and forwardly therefrom is a coin conducting tube 103, which terminates in a cup 104, outside the cabinet 10. The forward end of the slide bar 101 is suitably pivoted to one arm of a bell-crank lever 105. The other arm of the bell-crank 105, is pivoted to a depending link 106. The link 106 is pivoted to one arm of the bell-crank lever 107. On a shaft 108 is fixed an arm 109 extending adjacent to the drum 92 in such position that when the drum is rotated with bottles received in its pockets, the bottles will raise the arm 109 thereby rotating the shaft 108, and raising the arm 107 and link 106, and move the upper arm of the bell crank forwardly for drawing the slide bar 101 forward, thereby carrying a coin from the tube 99 to the tube 103.

It will be noted in the practical use of the form of the device shown in Figs. 7 and 8,

the rotation of the gear 32 caused by a full stroke of the lever 36, causes the mutilated gear 86 to move a fourth of a revolution from its position shown in Fig. 7, when an empty bottle is returned to the channel 93, and from there to the drum 92, and the lever 91 is pushed downwardly, the gear is moved through another one-fourth of a revolution and to position to be operated by the next movement of the gear 84. The movement of the drum 92 with the bottle contained therein, properly operates the coin delivering mechanism as hereinbefore referred to.

It will be understood that some changes may be made in the construction of my improved bottle vending machine without departing from its essential features, and it is my intention to cover by this application any such changes which may be included within the scope of my claims.

I claim as my invention.

1. In a bottle vending machine, a cabinet, a bottle holding and discharging magazine therein, a bottle receiving magazine, means for operatively connecting said magazines, whereby when the bottle holding and discharging magazine is moved to discharging position, the bottle receiving magazine is moved to receiving position.

2. In a device of the class described, a bottle vending mechanism comprising a cabinet having therein a bottle holding and feeding magazine, a drum mounted for rotation in said cabinet, having pockets, a guard for the lower portion of said drum, a water receptacle receiving the lower portion of said drum below the central axis thereof, the parts being so arranged that the drum receives and discharges the bottles above the water level in said receptacle, a bottle receiving drum having pockets, a discharging carrier adapted to receive bottles from said first drum, means for actuating said first drum, a bottle receiving device in the wall of said cabinet adapted to receive a bottle outside the wall and carry such bottle through said wall to position adjacent to said second drum, means for operatively connecting the first and second drums, whereby when the first drum is moved for discharging a bottle the second drum is moved to position where one of its pockets is in position to receive a bottle from said bottle receiving member.

3. In a device of the class described, a bottle vending mechanism comprising a cabinet having therein a bottle holding and feeding magazine, a drum mounted for rotation in said cabinet having pockets, a guard for the lower portion of said drum, a water receptacle receiving the lower portion of said drum below the central axis thereof, the parts being so arranged that the drum receives and discharges the bottles above the water level in said receptacle, a

bottle receiving drum having pockets, a discharging carrier adapted to receive bottles from said first drum, means for actuating said first drum, a bottle receiving device in the wall of said cabinet adapted to receive a bottle outside the wall and carry a bottle through said wall to position adjacent to said second drum, means for operatively connecting the first and second drums whereby when the first drum is moved for discharging a bottle, the second drum is moved to position where one of its pockets is in position to receive a bottle from said bottle receiving member, said means being so arranged that when said second drum is in its receiving position it may be rotated for a certain distance without effecting the first drum.

4. In a device of the class described, a bottle vending mechanism comprising a cabinet having therein a bottle holding and feeding magazine, a drum mounted for rotation in said cabinet having pockets, a guard for the lower portion of said drum, a water receptacle receiving the lower portion of said drum below the central axis thereof, the parts being so arranged that the drum receives and discharges the

bottles above the water level in said receptacle, a bottle receiving drum having 30 pockets, a discharging carrier adapted to receive bottles from said first drum, means for actuating said first drum, a bottle receiving device in the wall of said cabinet adapted to receive a bottle outside the wall 35 and carry a bottle through said wall to position adjacent to said second drum, means for operatively connecting the first and second drums, whereby when the first drum is moved to position where one of its pockets 40 is in position to receive a bottle from said bottle receiving member, said means being so arranged that when said second drum is in its receiving position, it may be rotated for a certain distance without affecting the 45 first drum, and means adapted to be actuated from outside the cabinet, whereby partial rotation may be imparted to said second drum when said second drum is moved to its receiving position. 50
